UNITED STATES PATENT OFFICE.

RAYMOND B. GILCHRIST, OF NEWARK, NEW JERSEY.

SQUEEZER.

1,053,590.

Specification of Letters Patent. Patented Feb. 18, 1913.

Application filed April 11, 1910. Serial No. 554,718.

To all whom it may concern:

Be it known that I, RAYMOND B. GILCHRIST, a resident of Newark, in the county of Essex and State of New Jersey, have invented certain new and useful Improvements in Squeezers, of which the following is a full, clear, and exact description.

The invention relates to lemon-squeezers, and designs, to provide improved mechanism for operating the presser-members; to provide improved mechanism for tilting the member on which the article from which the juice to be extracted is held, for convenience in placing the article on said member; or to discharge or remove it therefrom; to provide an improved means by which the pulp will, during the pressing operation be directed outwardly from the center of the lemon and inwardly from the outer edge thereof, so that the pulp will be disposed where the juice will be extracted therefrom by the rotation of one of the members with respect to the other, as distinguished from a device in which the pulp is directed to the center, wherein such action does not result; and further to provide a lemon squeezer of improved construction.

The invention consists in the several novel features hereinafter set forth and more particularly defined by claims at the conclusion hereof.

In the drawings: Figure 1 is a side elevation of a squeezer embodying the invention, the cover of the inclosing case or frame being removed, parts being shown in section, and showing the position assumed by the mechanism when the cup is disposed to receive a lemon and the operating-lever is in normal position. Fig. 2 is a similar view showing the mechanism in the position assumed when the lever has been operated to squeeze a lemon. Fig. 3 is a section taken on line 3—3 of Fig. 1. Fig. 4 is a horizontal section taken on line 4—4 of Fig. 1. Fig. 5 is a plan of the longitudinally movable presser-member. Figs. 6 and 7 are views similar to Figs. 1 and 2, but showing a modified form of the invention.

The improved lemon squeezer is of the "lever-operated" type and is mounted in a suitable frame or case which is usually provided with a clamp-screw 10 whereby it may be secured to a counter, table or shelf. This frame or case consists of a body-section 11,

in which the operating-mechanism is mounted, and a cover-section 12 adapted to fit against the other section, and to inclose the operating mechanism.

The squeezer comprises two coöperating presser-members, one of which is movable to and from the other to permit the lemon to be placed into position to be compressed, and for the purpose of bringing the members together to press an article therebetween. Press-member 13 is cup-shaped and is rotatably mounted in the frame but against vertical movement therein and is secured to the lower end of a shaft 14 which is journaled in said frame and is provided with a reduced upper end 15 which is journaled in a hardened bearing 16, which is adjustably connected, by a screw-thread 17 to the frame. The front portion of the body-section 11 of the frame is cylindrically shaped to contain said shaft. Shaft 14 is confined against longitudinal movement by a shoulder 18 on the shaft which is adapted to abut against the lower end of the hardened bearing 16 which serves as a thrust-bearing during the pressing operation, and a cotter-pin 19, which secures the shaft against downward movement in the frame. By removing said cotter-pin, member 13 and shaft 14 may be withdrawn from the case, and this permits said member to be easily cleaned. The other presser-member 20, which coöperates with rotatable member 13 is removably held in a holder 21, so that it can be conveniently removed whenever it may be desirable to cleanse it, said member 20 having a wall 22 having a shoulder 23 at its upper edge, which is adapted to fit upon the upper edge of the holder 21 and this member is also provided with a suitable handle 24 for convenience in manipulating it and a wall 22 is cut away at the front to permit the expressed article to be discharged or removed. Member 20 is perforated, as at 20^a to permit the juice to pass therethrough, into a conoidal guide 25 which is held in the holder 21 beneath said member and has a bottom-outlet 26 for directing the extracted juices into a receptacle held beneath it by any suitable means or in any suitable manner, as well understood in the art. This conoidal guide is removably held in the holder to permit its removal for cleansing.

The holder is provided with backwardly

extending lugs 27 at the upper and lower ends of which are journaled upper guide-rollers 28 and lower guide-rollers 29, which are adapted to travel in guide-ways 30 formed in each side of the case, one pair of these rollers being disposed at each side of the lugs and these rollers are mounted on cross-pins 31 secured in the lugs on the holder. The lower portion of each of these 10 guide-ways is curved backwardly as at 30^a to cause the holder and presser-member held thereby, to be tilted downwardly, so that during the lower portion of the stroke of the operating-mechanism, the holder and presser-member held therein, will be tilted to discharge the lemon held thereby or to facilitate the insertion of the lemon and the removal of the lemon-rind, and during the upper part of such stroke it will travel vertically. Resultantly, when the holder is in normal position, as shown in Fig. 1, it will be conveniently disposed to receive a section of a lemon, and during the operation of the holder, it will be raised and brought into 20 proper position for the pressing operation beneath presser-member 13 and after each pressing operation, the holder will be tilted downwardly sufficiently to cause the squeezed rind to fall off of presser-member 20 or to facilitate its removal. At the lower 30 end of guides 30, abutments 33 are disposed to arrest the rollers 29 and limit the downward and tilting movement of the holder.

35 A lever or handle 36 is provided for operating the squeezer. This lever is secured to the outer end of a shaft 37 which is journaled in a bearing 38 formed in the body-section of frame 11. An oblique toothed 40 gear 39 is integrally formed with shaft 38 and is disposed within the case. The oblique teeth of this gear mesh with worm-teeth 40 formed on shaft 14 of presser-member 13 to cause the latter to be rotated horizontally 45 when wheel 39 is rotated by the lever, the shaft being secured against horizontal movement by the thrust-bearing 17 and pin 19, as hereinbefore set forth. Resultantly, when the lever is operated in either direction, 50 presser-member 13 will be rotated.

A flexible operating connection is provided between wheel 39, which is operated by the lever 36, and the holder 21, and in the preferred embodiment of the invention, 55 this connection consists of a linkage between the holder 21 which carries the presser-member 20 which is movable to and from member 13, and the operating-lever 36, so that the member 20 will be operated to and from 60 the rotatable member 13. This linkage consists of a short member 42 which is pivotally connected as at 43, to wheel 39 which moves with the operating lever, and at its other end, as at 44, to a longer member 45, 65 which is pivoted at 31 to holder 21. When

the connection is in its normal position, as seen in Fig. 1 and the lever is operated in forward direction, pivot 43 will move upwardly in the direction of the arrow indicated in Fig. 1 and the connection will 70 raise the holder 21, and rollers 29 traveling in the curved portion 30^a of guide-ways 30, will cause the holder and presser-member therein to swing into substantially horizontal position during the initial upward movement of the linkage. During further operation of the lever and after presser-member 20 has been brought into proximity of member 13 and the initial squeezing has been effected, an abutment 47 on wheel 39 will engage the 75 member 42 and cause it to travel in fixed relation with said wheel so that pivot 44 between members 42, 45 will become operative as a slightly eccentric pivotal connection for 80 effectively bringing the presser-members together for the final squeezing. This pivot 44 is at such time disposed a short distance from the axis of shaft 37 acting as an eccentric connection of a short radius, so that a 85 very effective and great leverage results during the latter portion of the pressing operation. This mechanism therefore operates as a differential connection consisting of 90 constantly connected parts, and whereby a long eccentric connection is utilized during 95 that portion of the operating stroke of the lever, when a rapid stroke is desired, and a short eccentric connection and a greatly increased leverage are attained during that portion of the pressing operation when the 100 final compression is effected. Wheel 39 is provided with a step 48 to arrest it when it 105 encounters link 45, as shown in Fig. 2 and serves to arrest the movement of wheel 39 and the operating-lever. It will thus be seen that this connection constituted of link-members operates as a flexible connection between wheel 39 and the holder 21 and this connection will be differentially operated 110 during the operation of the lever to effectively apply the power for a squeezing operation. The holder, being guided vertically, will descend by gravity during the retraction of the operating lever.

Presser-member 20, which is brought into 115 operative relation with respect to compressor-member 13 and which is rotated by the operating lever, is of conoidal form and its upper face is provided with an inner series of tangentially disposed straight ribs 120 50 and an outer series of oppositely disposed tangential ribs 51, a groove being formed between the outer ends of the inner series of ribs 50 and the inner ends of the outer series of ribs 51. As a result of this 125 formation of ribs on the presser-member 20, the pulp adjacent the outer edge of the rind will be caused to move inwardly a slight distance to or toward groove 52 and the pulp adjacent the center of said member will be 130

caused, by the rotation of member 13 above the rind and ribs 50, to pass outwardly from the center, to groove 52, and this formation prevents any pulp from passing to the center of the member where it would not be subjected to the rotative action of presser-member 13.

The operation of the improved squeezer will be as follows: Assuming the parts to be in the position shown in Fig. 1 and a section of a lemon or article to be pressed to have been placed on presser-member 20, lever 36 will be rotated forwardly and such shift of the lever will rotate wheel 39 and the oblique teeth on wheel 39 will cause shaft 14 to be rotated continuously. During the initial movement of the operating lever, connection 42, 45 will raise holder 21 and the latter will be brought into substantial horizontal position, as rollers 29 move upwardly in the curved portions 30^a of guide-ways 30 and when said rollers have passed into the straight portion of said guide-ways, the presser-member 20 will be properly positioned to move directly toward the rotating presser-member 13. This initial movement of member 20 is quickly effected by eccentric-connection 43 until abutment 47 engages the connection member 42, when the initial squeezing will have been effected, and the presser-members will then be in close proximity to each other. Next, the flexible connection 42, 45 will operate differentially, pivot 44 then operating as a short eccentric-connection to impart a relatively slow and powerful stroke to presser-member 20 and thus great leverage for the final pressing operation is attained when desirable. During the pressing operation and after the lemon has been brought into contact with rotating presser-member 13, the latter which is provided with ribs 13^a will, by reason of its rotation of the lemon-rind, cause the pulp near the central portion of the lemon to be directed outwardly to groove 52 and the pulp from the outer portion of the lemon to be directed inwardly to said groove, so that the pulp will be subjected not only to direct pressure between the members, but to the rotative squeezing action of rotating member 13.

The invention thus provides a simple and efficient operating mechanism for bringing one of the presser-members toward the other and whereby a differential leverage is obtained for effecting a quick stroke during the initial movement of the presser-member and a greater and more effective leverage is attained during the final squeezing operation. The invention also provides simple and efficient means for tilting the presser-member on which the article to be pressed is placed, so that it will be tilted to discharge the rind. The invention also provides an improved form of presser-member,

which will cause the pulp to be directed outwardly from the center of the lemon to subject it to the rotative action of the rotating compressor-member.

In Figs. 6 and 7 there is shown a modified form of the invention, in which the longitudinally movable presser-member and holder are tilted slightly to facilitate placing a lemon therein, this modification being different from that already described in that the guides for the rollers on the holder are curved slightly to tilt the holder merely sufficiently to permit a section of the lemon to be placed therein and the presser-member 20^c has a complete surrounding wall 22^b for holding the lemon and rind on the member 20.

The invention is not to be understood as restricted to the details shown and set forth, since these may be modified within the scope of the appended claims, without departing from the spirit and scope of the invention.

Having thus described the invention, what I claim as new and desire to secure by Letters Patent is:

1. In a squeezer, the combination of a frame, two presser members supported thereon, one of said members being movable relatively to the other, an operating lever, means operated by the lever for rotating one of the members, and a connection for operating the other of said members by the lever, said connection being flexible between the point at which it is connected to the member operated thereby and the point where it is connected to the lever.

2. In a squeezer, the combination of two presser-members, one of which is movable relatively to the other, an operating lever, a flexible connection for operating one of said members by the lever, and means for causing said connection to operate differentially in shifting the latter member.

3. In a squeezer, the combination of two presser-members, one of which is movable relatively to the other, an operating lever, a gear-connection for rotating one of said members, and a connection between said lever and one of said members said connection being flexible between its ends.

4. In a squeezer, the combination of two presser-members, one of which is movable relatively to the other, an operating lever, a gear-connection for rotating one of said members, a flexible connection for operating one of said members by the lever, and means for causing the flexible connection to operate differentially in shifting the member operated thereby.

5. In a squeezer, the combination of two presser-members, one of which is movable relatively to the other, an operating lever, means operated by the lever for operating one of said members, and a connection for operating the other of said members by the

- lever, the latter member being mounted so it will be lowered by gravity said connection being flexible between its ends.
6. In a squeezer, the combination of two presser-members, one of which is movable relatively to the other, an operating lever, a flexible connection for operating one of said members by the lever, the member operated by said connection being mounted to be shifted in one direction by gravity, and means for causing the connection to operate differentially in shifting the member operated thereby.
7. In a squeezer, the combination of two presser-members, one of which is movable relatively to the other, an operating lever, a gear connection for rotating one of said members, and a connection for operating one of said members by the lever, the latter member being mounted so it will be lowered by gravity said connection being flexible between its ends.
8. In a squeezer, the combination of two presser-members, one of which is movable relatively to the other, an operating lever, a gear connection for rotating one of said members, a flexible connection for operating one of said members by the lever, the member operated by said connection being mounted to be shifted in one direction by gravity, and means for causing the connection to operate differentially in shifting the member operated thereby.
9. In a squeezer, the combination of two presser-members, one of which is movable relatively to the other, an operating lever, a connection for rotating one of said members by the lever, and a connection for operating the other of said members comprising a plurality of serially connected links.
10. In a squeezer, the combination of two presser-members, one of which is movable relatively to the other, an operating lever, a connection for operating one of said members comprising a plurality of connected links, and means for causing the connection to operate said member differentially.
11. In a squeezer, the combination of a frame, a pair of coöperating presser-members, one of which is movable to and from the other, an operating lever pivoted in the frame, a connection between said lever and a presser-member comprising a plurality of connected links, and means for causing one of the links to travel in fixed relation to the lever the latter link being pivoted to the lever at a point eccentric to the lever fulcrum, and swinging into position to cause the lever to act on the connection with a greater leverage.
12. In a squeezer, the combination of a frame, a pair of coöperating presser-members, one of which is movable to and from the other, an operating lever pivoted in the frame, a connection between said lever and
- a movable member comprising a plurality of connected links, and an abutment operated by the lever for engaging one of the links to cause the connection to operate differentially.
13. In a squeezer, the combination of a frame, a pair of coöperating presser-members, one of which is movable to and from the other, an operating lever pivoted in the frame, and a connection between said lever and one of said members consisting of a plurality of differentially operating connected links, and a gear-connection for rotating one of said members.
14. In a squeezer, the combination of two presser-members, one of which is movable relatively to the other, an operating lever, a connection for operating one of said members comprising a plurality of links, means for causing the connection to operate said member differentially, and a gear-connection operated by the lever for rotating one of the members.
15. In a squeezer, the combination of a frame, a pair of coöperating presser-members, one of which is movable to and from the other, an operating lever pivoted in the frame and a connection between said lever and a movable member consisting of a plurality of connected links, means for causing one of the links to travel in fixed relation to the lever, and a gear-connection operated by the lever, for rotating one of the members.
16. In a squeezer, the combination of a frame, a lever pivoted in the frame, a presser-member held against longitudinal movement in the frame, a shaft connected to said member, a worm gear on said shaft, a gear operated by said lever and engaging the worm on the shaft to rotate said member, another presser-member longitudinally slidably mounted to move to and from the rotating member, and a connection between the lever and the longitudinally movable member, for bringing it to and from the rotating member said shaft and worm being disposed in front of said gear.
17. In a squeezer, the combination of a frame, a lever pivoted in the frame, a presser member held against longitudinal movement in the frame, a shaft connected to said member, a worm gear on said shaft, a gear operated by said lever and engaging the worm on the shaft to rotate said member, another presser member longitudinally movable to and from the rotating member, and a serial linkage between the lever and the longitudinally movable member said shaft and worm being disposed in front of said gear.
18. In a squeezer, the combination of a frame, a lever pivoted in the frame, a rotatable presser-member, gear mechanism operated by the lever, for rotating said member, a longitudinally movable presser-mem-

ber operatively connected to said lever, and means for tilting the longitudinally movable member.

19. In a squeezer, the combination of a frame, a lever pivoted in the frame, a rotatable presser-member, gear mechanism operated by the lever, for rotating said member, a longitudinally movable presser member operatively connected to said lever slidably mounted, and means for tilting the longitudinally movable member.

20. In a squeezer, the combination of a frame, a lever pivoted in the frame, a rotatable presser-member, gear mechanism operated by the lever, for rotating said member, a longitudinally movable presser-member operatively connected to said lever, rollers on the latter member and guided in said frame, and means for tilting the longitudinally movable member.

21. In a squeezer, the combination of a frame, a lever pivoted to the frame, a rotatable presser-member, gear mechanism operated by the lever, for rotating said member, a longitudinally movable presser-member, a link-connection between the lever and said longitudinally movable member, and means for tilting said member as it is operated by said connection.

22. In a squeezer, the combination of a frame, a lever pivoted in the frame, coöperating presser-members, one of which is longitudinally movable, guides in said frame, means on said latter member sliding in said guides and for guiding and tilting said longitudinally movable member, and a connection between said longitudinally movable member and the lever.

23. In a squeezer, the combination of a frame, a lever pivoted in the frame, coöperating presser-members, one of which is longitudinally movable, and guides in said frame for guiding and tilting said longitudinally movable member, rollers on said member traveling in said guides, and a connection between said longitudinally movable member and the lever.

24. In a squeezer, a conoidal presser-member having a series of tangential ribs disposed to direct the pulp outwardly from the central portion thereof, and a series of ribs, disposed to direct the pulp inwardly from the outer portion thereof.

25. In a squeezer, a conoidal presser-member having a series of tangential ribs disposed to direct the pulp outwardly from the central portion thereof, and a series of ribs,

disposed to direct the pulp inwardly from the outer portion thereof, and having a groove between said series of ribs.

60

26. In a squeezer, the combination of a lever, a pair of coöperating presser-members, one of which is operated by the lever to bring them together, mechanism operated by the lever for rotating one of the members, one of said members having a series of tangentially disposed ribs for directing the pulp outwardly from the center thereof, and a series of oppositely disposed ribs for directing the pulp adjacent the outer portion of the member inwardly.

65

27. In a squeezer, the combination of a lever, a pair of coöperating presser-members, one of which is operated by the lever to bring the members together, mechanism operated by the lever for rotating one of the members, one of said members having a series of tangentially disposed ribs for directing the pulp outwardly from the center thereof, and a series of oppositely disposed ribs for inwardly directing the pulp adjacent the outer portion of the member, said member having a groove between the inner and outer series of ribs.

80

28. In a squeezer, the combination of a frame, a lever pivoted in the frame, a vertically extending shaft journaled in the frame and extended above the frame, a rotatable presser-member connected to the lower end of said shaft, a removable pin for holding said presser-member in operative position and extending through the shaft above the frame, said member being free to fall downwardly when the pin is removed, a gear-connection between said lever and said shaft, a presser-member movably mounted in the frame, and a connection for bringing said latter member to and from the rotating member.

85

29. In a squeezer, the combination of a frame, a lever pivoted in the frame, a shaft journaled in the frame, a rotatable presser-member secured to the lower end of the shaft, a thrust-bearing for said shaft, a gear operated by the lever, a worm-gear on said shaft and engaged by said lever-operated gear, said shaft and worm being disposed in front of said gear and a presser-member coöperating with said rotatable member.
